(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a display screen or portion thereof with animated graphical user interface showing our new design; FIG. 2 shows a second image thereof; and, FIG. 3 shows a third image thereof.

The peripheral dashed broken lines illustrate a display screen or portion thereof, and form no part of the claimed design.

The appearance of the graphical user interface transitions sequentially between the images shown in FIGS. 1-3. The process or period in which one image transitions to another forms no part of the claimed design.
